UNITED STATES PATENT OFFICE.

JOHN H. STEWART AND JOHN M. SCHENK, OF WATERLOO, IOWA, ASSIGNEES TO THE
CEMENT TILE MACHINERY COMPANY, OF WATERLOO, IOWA.

CONCRETE-MIXER.

1,185,948.

Specification of Letters Patent. Patented June 6, 1916.

Application filed March 3, 1916. Serial No. 81,888.

To all whom it may concern:

Be it known that we, JOHN H. STEWART and JOHN M. SCHENK, citizens of the United States of America, and residents of Waterloo, Blackhawk county, Iowa, have invented 5 certain new and useful Improvements in Concrete-Mixers, of which the following is a specification.

Our invention relates to improvements in 10 concrete mixers, and the object of our improvement is to so support an open-ended rotatable tilttable mixing-drum in such a machine as to place it in a balanced condition when loaded, in rotation, and while being 15 tilted to deliver its contents. This object we have accomplished by the means which are hereinafter described and claimed, and which are illustrated in the drawing hereto annexed, which is a front elevation of a concrete-mixer of the type mentioned, showing 20 the mixing-drum and a portion of the supporting-means therefor in vertical central section.

The mixing drum shown is of a cup-shape 25 having a common receiving and delivery opening at the top, the upper parts 1 of the drum being connected to the lower part 2, the latter being preferably formed of a single casting while the other parts may be 30 formed of sheet iron. An annular bevel gear 15 is fixed around the middle part of said drum and is in mesh with a bevel pinion 16 mounted on a short shaft rotatably seated in the upper end of one of the side 35 standards 13 of the machine frame, said shaft also carrying a belt wheel 17 on its outer end. The fixedly connected standards 13 may be mounted on skids or blocks 18, or on any other desired supporting means. 40 The central part of the bottom of the drum base 2 is inverted axially and tubularly at 3 and so as to occupy but little space in the interior of the drum while extending thereinto approximately to the tilting axis 45 of the drum.

The numeral 4 denotes a downwardly bowed rock-shaft, one end of which is suspended pivotally on the shaft which carries the bevel pinion 16, while the other end has 50 a trunnion pivotally supported in a bearing in the upper part of the other standard 13, and having a crank handle 14 fixedly secured on its outwardly extending end.

The bowed part of the rock-shaft 4 has 55 an integral cylindrical projection 7 extend-

ing toward the axis of the shaft and located axially with relation to said mixing drum. Said projection 7 extends into the hollow of the inverted part 3 of said drum, the rock-shaft, its projection 7, and the upper end of 60 the inverted bottom 3 being orificed in line axially to seat a pivot-shaft 5. The pivot-shaft is connected to the rock-shaft and to the bottom of said drum at opposite ends by means of the nuts 6 and 10 respectively. 65 The lower wall of the upper part of the tubular extension 3 bears rotatably upon anti-friction balls 8 seated in a raceway between it and the upper end of the projection 7, but said balls may be omitted, if desired, in 70 the smaller and lighter sizes of machines.

An oil-cup 12 communicates with a longitudinal duct 11 in the projection 7 to supply said raceway bearing.

While, for purposes of convenience in 75 illustration, the mixing-drum 1—2 is shown opening vertically, yet it is understood that in practice, it is somewhat tilted to mix efficiently, while rotating. When the contents of the drum have been sufficiently 80 mixed, its contents may be dumped by using the handle or crank 14 to tilt the rock-shaft 4.

It will be observed that the pivotal bearing connection of said drum with the bowed 85 rock-shaft 4 is at the extremity of the projection 7 of said shaft, that is, said pivotal connection is located relatively to said drum and shaft approximately in line with the axis of said shaft or near enough thereto to 90 permit of a balanced condition of the drum when loaded and being tilted up or down. This balanced condition is also attained when the drum is not loaded, but the principal benefit accruing from this method of 95 mounting the drum is obtained when the drum is being tilted in a loaded condition, since much less labor and effort is needed where the support of the drum is near the center instead of at its base, for, in the latter case, there is a greater amount of leverage to be overcome, which is a serious matter when the machine is manually tilted.

The pivot-shaft 5 rotates with the drum 1—2, the upper part of the tubular projection 3 of the drum being tightly clamped 105 between the nut 10 and the shoulder of said shaft, and which also seals hermetically the connection of said parts. Since the shaft 5 has a relatively long bearing within the tu- 110

bular projection 7 of the rock-shaft, friction is diminished, and a very strong supporting means formed at that location for the drum. This adds to the stability and length of life 5 of the drum and its bearings.

Having described our invention, what we claim as new, and desire to secure by Letters Patent, is:

The combination in a concrete-mixer, of a 10 tilttable rotatable mixing-drum formed with a central inverted cup-shaped bottom part, and supporting-means projected into said

cup-shaped part axially and connected thereto for the drum to rotate thereon at its extremity approximately in line with the 15 axis of tilting of the drum, to balance the loaded drum while being tilted.

Signed at Waterloo, Iowa, this 25th day of Feb. 1916.

JOHN H. STEWART.
JOHN M. SCHENK.
